UNITED STATES PATENT OFFICE.

LEONIDAS L. LANDIS, OF HARRISON TOWNSHIP, NEAR DAYTON, OHIO.

AUTOMATIC CUE-CHALKER.

1,160,988.

Specification of Letters Patent. Patented Nov. 16, 1915.

Application filed March 2, 1915. Serial No. 11,575.

To all whom it may concern:

Be it known that I, LEONIDAS L. LANDIS, a citizen of the United States, residing in the township of Harrison, near the city of Dayton, in the county of Montgomery and State of Ohio, have invented new and useful Improvements in Automatic Cue-Chalkers, of which the following is a specification.

This invention relates to new and useful improvements in automatic cue chalkers.

The object of the invention is to provide a device for readily and effectively chalking a cue without the necessity of handling the chalk in any manner. By the use of my device for this purpose, the hands or clothes will not be soiled, there is no possibility of chalk falling upon the tables, and a cue may be thoroughly chalked with a minimum amount of effort and time.

The preferred form of embodiment of my invention is illustrated in the accompanying drawings, of which—

Figure 1 is an elevational view of my improved cue chalker. Fig. 2 is an elevational view, partly broken away, of that portion of the device which contains the chalk. And Fig. 3 is an elevational view, partly broken away, of the upper portion of said device.

Throughout the specification and drawings, similar reference characters denote corresponding parts.

In a detailed description of the preferred form of embodiment of my invention, the numeral 1 designates an elongated rod or support, circumferential in cross section and preferably constructed of cast iron. The upper end of the rod 1 is threaded to receive the threaded cylindrical portion of a boss 2 preferably cast integral with the central portion of a plate 3. This plate is adapted, by means of screws 4 passing through apertures 5 therein, to be firmly attached to a solid body 6, such as a ceiling or wall. (See Fig. 3.)

Passing horizontally through the extreme lower end of the rod 1, and projecting a short distance beyond each side of said rod, is a pin 7 for a purpose to be now described.

The numeral 8 designates a tubular member or sleeve terminating at its lower end in an enlarged cylindrical portion 9. This cylindrical portion 9 is so formed as to

provide a lower bore of larger diameter than another formed above it, thereby producing a circumferential shoulder or flange 10, against which a piece of cue chalk 11 is adapted to be forced after being inserted in the lower end of said cylindrical portion. Adapted to be pressed into the lower end of the cylindrical portion 9 of the sleeve 8, to hold the cue chalk therein, is the tubular neck portion 12 of a funnel-shaped member 13. This member 13 is adapted to be readily and firmly secured to the cylindrical portion 9 by means of a set screw 14, after the chalk 11 is in place within the former. (See Fig. 2.) The member 13 also serves the purpose of guiding the cue to the chalk with which it is thoroughly covered as follows.

The lower end of the rod 1 is adapted to loosely project into the tubular member 8. Formed in this member is a spiral slot 15 which the pin 7 is adapted to loosely enter, to turn said member when the latter travels upwardly and downwardly upon the rod 1. Accordingly, when the end of a cue 16 is forced against the chalk 11 and the cue is elevated, said chalk will be rotated by reason of its firm contact with the shoulder 10 of the cylindrical portion 9, which is rotated by the slot and pin construction just described.

The tubular member 8 may be moved upwardly by the cue 16 until the pin 7 rests in the extreme lower end of the slot 15, whereupon said member may be permitted to descend by gravity until said pin is in the lowermost end of the aforesaid slot. During this upward and downward movement of the tubular member 8, the chalk 11 will be rotated sufficiently to thoroughly cover the end of the cue therewith. It is thus a very simple operation to chalk a cue with my device, it merely being necessary to thrust the end of the cue through the member 13, into contact with the chalk, then pressing upwardly on said cue, and afterward permitting it to descend, with the result that the end of the cue will be thoroughly covered with the rotating chalk. The chalk, therefore, does not come in contact with the hands or clothing, nor is there any danger of any particles of the chalk falling upon the pool or billiard tables to soil the latter.

To prevent any particles of the chalk

from entering the upper portion of the device, a piece of cardboard 17 is preferably placed between the chalk 11 and the shoulder 10 to completely seal the opening above, 5 as shown in Fig. 2.

While I preferably construct my improved cue chalking device of cast iron, it may be made of any other suitable material; nor do I wish to be limited to the details 10 of construction and arrangement herein shown and described, as the same may be varied within the scope of the subjoined claims.

Having described my invention, I claim: 15
1. An automatic chalking device, comprising a depending rod adapted to be attached to a solid body, a sleeve longitudinally movable over the lower end of said rod, said sleeve terminating in a cylindrical portion adapted to receive a piece of chalk, a shoulder formed in said cylindrical portion, against which said chalk is adapted to be pressed by a cue, said sleeve being provided 20 with a spiral slot, a pin in said supporting member adapted to enter said slot and turn said cylindrical portion and chalk 25

when pressure is exerted against the latter by a cue, substantially as described.

2. An automatic chalking device comprising a rod adapted to be attached to a solid body; a sleeve longitudinally movable over the lower end of said rod, said sleeve terminating in a cylindrical portion adapted to receive a piece of chalk, a shoulder formed in said cylindrical portion, against which said chalk is adapted to be pressed by a cue, a funnel shaped guide removably attachable to the lower end of said cylindrical portion to normally hold said chalk against 30 said shoulder, said sleeve being provided with a spiral slot, and a pin on said rod adapted to enter said slot to turn the cylindrical portion of the sleeve and chalk when pressure is exerted against the latter 35 by a cue, substantially as described. 40

In testimony whereof I have hereunto set my hand this 1st day of March, 1915.

LEONIDAS L. LANDIS.
